TERMAL ELECTRIC CUT-OUT.

REISSUED

1,261,256.

Specification of Letters Patent.

Patented Apr. 2, 1918.

Application filed November 20, 1914. Serial No. 873,216.

To all whom it may concern:

Be it known that I, ROY H. MAPLE, a citizen of the United States, and a resident of Indianapolis, county of Marion, and 5 State of Indiana, have invented a certain new and useful Thermal Electric Cut-Out; and I do hereby declare that the following is a full, clear, and exact description thereof, reference being had to the accompanying 10 drawings, in which like letters refer to like parts.

The object of this invention is to provide a thermo-electric circuit breaker or cut out which has a very few number of parts and 15 is designed primarily for use on low voltage circuits, such as those used with battery illumination. This form of circuit breaker has a high momentary overload capacity for short periods of time and in low voltage 20 lamp circuits the extremely low resistance of the filaments causes a heavy flow of current until they become sufficiently heated to cause a circuit breaker, not having the characteristics mentioned, to be set beyond this 25 peak current load. The setting of a circuit breaker for this momentary overload would render it useless for small overloads such as caused by grounds and partial short 30 circuits. The type described in this application will operate successfully if any load above the normal is continued for any length of time.

Another feature of the invention consists in forming such a device so that it will perform the above function and without changing circuits as an ordinary switch. In this 35 last mode of operation of the device, the thermostat does not operate. In other words, the device operates as an ordinary 40 switch when the thermostat is carrying the regular load. The free end of the thermostat cooperates with the movable switch member in making the circuit and another resetting movable member moves the free 45 end of the thermostat out of engagement with the free end of the switch member for breaking the circuit. So this forms an ordinary "make and break" switch and yet the circuit will be automatically broken on 50 the occasion of temperature change influencing the thermostat. The device, therefore, is a combined thermostatic switch and manually operated switch.

The full nature of the invention will be understood from the accompanying drawings and the following description and 55 claims.

In the drawings, Figure 1 is a side elevation of the switch with the parts in circuit closing position and with parts in section. Fig. 2 is an elevation of the right-hand end of Fig. 1 and showing two switches and both switches closed and with parts in section. Fig. 3 is a plan view of the device shown in Fig. 2 with the top 60 plate removed. Fig. 4 is a plan view of Fig. 2 including the top plate. Fig. 5 is a section like Fig. 1 of a modified form. Fig. 6 is a perspective view of the end of the 65 thermal spring.

In the drawings herein shown there is a base plate 10 formed of hard rubber and having in it a binding post 11 which also screws upon the plate 10. There is a spring switch member 12 consisting of a plate 75 formed of spring metal and with the two sides thereof bent upward so as to press against each other normally and with the upper ends spread away from each other somewhat to permit the entrance between 80 them of the movable member 13 of the switch. This makes substantially a knife switch and may be made in any suitable form, as the invention is not limited to any particular construction of the switch members. The movable switch member 13 has secured to it a hard rubber push button 14 that reciprocates through a plate 15. It also has an inwardly extending arm 17 which is angular in cross section and extends through a correspondingly shaped 85 hole in the base plate 10 and reciprocates therein. A spring 18 is located around the arm 17 and lies between the plate 10 and the switch member 13 and its function is to 90 return or force outward said switch member after it has been forced inward and released. The switch member 13 has a nose piece 20 on it with a curved edge or surface, as shown in Fig. 1, adapted when the 95 switch member 13 is pushed inward to pass below the free end 21 of a thermal strip 22. When the switch member 13 is in such inward position, it will be held there in spite of the action of the spring 18, by 100 105 said end 21 of the thermostat until said

end of the thermostat is moved so as to release the switch member 13 and then the spring 18 returns it and breaks the circuit.

The thermal strip 22 is coiled about a 5 horizontal arm 25 extending from a vertical stand 26. The horizontal arm is slotted to receive the inner end of the thermal strip and then said strip is coiled about the same and the free end of the strip is bent back 10 on itself to enlarge said end and provide a curved surface and also provide engagement members for trip member 35 on the end thereof for engaging the curved surfaces of the nose 20 of the switch member 13. The end of the thermal strip is located 15 so as to engage the nose of the switch member 13 and as the switch member 13 is pushed inward the end 21 of the thermal strip passes the point of the nose 20 and 20 engages the surface on the upper or outer side of said nose and holds the switch member 13 inward in circuit making position. To insure the circuit passing effectively from the thermal strip to the switch member 13 a pig tail 27 is provided connecting 25 them substantially as shown in Fig. 1, and arranged so as not to interfere with the movements of the two members of said parts.

30 The plates 10 and 15 are held spaced apart by suitable posts or screws 127. The parts of the mechanism so far described operate as a thermostatic switch. In normal position the circuit is broken. When, however, the 35 switch member 13 is pushed inward, the parts assume the position shown in Fig. 1 and the circuit is closed by the knife edge of the member 13 entering between the spring contacts 12 and the thermal strip 40 will hold the parts 12 and 13 in electrical connection until the thermal strip 22 is heated causing it to expand and to some extent unwind, thus moving the end 21 of said thermal strip away from the nose 20 45 of the switch member 13. Then the switch member 13 returns to normal position under the action of the spring 18 and out of engagement with the spring contacts 12.

To enable said thermostatic device to be 50 used also as an ordinary manually operated switch there is a lateral projection 30 from the free end of the thermal strip in position to be engaged by a shoulder 31 and push rod 32 mounted in the plates 10 and 15. An extension 33 on said push rod 32 reciprocates 55 in the base plate 10 and the push rod is returned by a spring 34 lying between the shoulder 31 and the plate 10.

Assuming that the circuit has been operated 60 so as to close the circuit by depressing the button 14 on the switch member 13, and it is desired to break the circuit manually, the push button 35 is operated by releasing the free end of the thermal strip so that it 65 ceases to hold the switch member 13 in

engagement with the contact springs 12. The spring 34 immediately returns the push button 35 to its normal position. In order that the free end of the thermal strip may more effectually engage and hold the switch 70 member in circuit closing position, the switch member is provided with a notch 40 above its end and with a substantially regular curvature into which the bent free end of the thermal strip lies. The effect of this 75 is that the notch provides a shoulder against which the free end of the thermal strip bears so that when the strip is heated, said engaging end will move away from the switch member at a substantially right angle to the 80 portion thereof which it had been engaging.

Locking means is also provided consisting of the laterally movable bolt 41 mounted in the casing adapted to be operated by any suitable key 42 so that when the bolt is actuated, it will engage a notch 43 in the end 85 of the switch member and prevent its operation or movement.

The arm 26 is held in place and from turning by being made angular so as to have 90 a lower plate that sets down in the recess 42 in the base 10 and is secured thereto by a screw 43', as seen in Fig. 3.

The invention claimed is:

1. A thermal switch having a coiled thermal strip in the circuit thereof, a movable switch closing member in position to be held closed by the free end of said thermal strip, a spring for returning said switch member after its release, and means for positively 100 disengaging the free end of the thermal strip from said switch member.

2. A switch having a coiled thermal strip in the circuit thereof, a movable switch closing member in position to be closed by the 105 free end of said thermal strip, a spring for returning said switch member after it is released, a push rod for disengaging the free end of the thermal strip from said switch member and releasing it, and means for returning said push rod.

3. A switch including a coiled thermal strip in the circuit thereof, a lateral projection near the free end of said strip, a movable switch member for closing the circuit 115 and in position to be held closed by the free end of said thermal strip, a push rod for engaging the lateral projection from the thermal strip and moving it so as to release the switch member, and means for returning 120 the switch member and push rod to normal position.

4. A switch including a coiled thermal strip in the circuit thereof, a lateral projection near the free end of said thermal strip, 125 a movable switch member for closing the circuit and in position to be held closed by the free end of said thermal strip, a push rod for engaging the lateral projection from the thermal strip and moving it so as to release 130

the switch member, and springs for returning the switch member and push rod to normal position.

5. A thermal switch having an arm, a thermal strip secured at one end to said arm and coiled about the same with the free end of said strip bent back on itself, and a movable switch member having an inwardly turned end provided with a curved notch into which said curved free end of the thermal strip is adapted to enter and hold the switch member closed, the parts being arranged so that the releasing movement of the free end of the thermal strip will be substantially at a right angle to the portion of the switch engaged thereby.
6. A thermal switch having two parallel separated plates in fixed relation to each other, a thermal strip mounted between said plates and with one end thereof secured in fixed position and the other end thereof free, a contact located between said plates, a switch member slidably and non-rotatably mounted in said plates in position to be moved into and out of engagement with the free end of said thermal strip and with said

contact, and a spring for returning said switch member after it has been moved into such engagement.

7. A thermal switch having two parallel separated plates in fixed relation with each other, a coiled thermal strip mounted between said plates and with one end thereof secured in fixed position and the other end thereof free, a contact between said plates and in fixed relation therewith and with said thermal strip, a push rod extending through said plates and arranged so as to be non-rotatable, a switch member secured on said push rod so as to be movable thereby into position to engage both the free end of said thermal strip and said contact, and a spring on said push rod for returning the same and the switch to normal outward position.

In witness whereof, I have hereunto affixed my signature in the presence of the witnesses herein named.

ROY H. MAPLE.
